THROTTLE CONTROL DEVICE FOR
INTERNAL-COMBUSTION ENGINES

Sydney Macdonald Parker, Leamington Spa, England, assignor to Automotive Products Company Limited, Leamington Spa, England

Application September 17, 1951, Serial No. 246,919

6 Claims. (Cl. 192—062)

1

This invention relates to throttle control devices for internal combustion engines, and has for its object to provide a device, independent of the normal throttle control mechanism, which temporarily limits to a predetermined range the possible setting of the throttle. The device is primarily intended to provide an appropriate setting of the throttle during the changing of gears in a variable-speed gear box associated with an engine, being operated for that purpose by the change speed gear control.

According to the invention a throttle control device includes at least one stop which is movable into its operative position to limit the range of movement of the throttle valve upon actuation of a control other than the normal throttle control, the said stop, in moving to its operative position, adjusting the throttle valve independently of the normal throttle control if the position of the latter is such as to position the throttle valve at a setting outside the limited range.

Further, according to the invention a throttle control device for the engine of a vehicle includes at least one stop which is movable into its operative position to limit the range of movement of the throttle valve upon operation of a change-speed gear control to disengage a gear and returned to a position in which it does not obstruct movement of the throttle valve through its full normal range when a gear is engaged, the said stop, in moving to its operative position, adjusting the throttle valve independently of the normal throttle control if the position of the latter is such as to position the throttle valve at a setting outside the limited range.

The throttle valve is preferably positively connected to a member co-operating with the stop, and the normal throttle control mechanism acts on the said member through a resilient element so that the member can move independently of such mechanism.

Two stops may be provided one of which, in its operative position, defines the upper limit of a range of movement of the throttle valve the other limit of which is the closed position of the said valve, whilst the other, in its operative position, defines the lower limit of a range of movement of the throttle valve of which the other limit is the maximum normal throttle opening.

The invention is hereinafter described with reference to the accompanying drawings, in which:

Figure 1 is a diagram showing one form of throttle control device according to the inven-

2

tion, together with parts of a gear-changing mechanism with the operation of which the throttle control device is associated;

Figure 2 is a detail view showing a pair of switches operated by the gear-changing mechanism of Figure 1;

Figure 3 is a side elevation of the throttle control device shown diagrammatically in Figure 1;

Figure 4 is a section on the line 4—4 of Figure 3;

Figure 5 is a plan view of the device shown in Figure 3;

Figure 6 is a diagram, similar to Figure 1, showing another form of throttle control device according to the invention, and parts of the gear-changing mechanism with which it is associated;

Figure 7 is a side elevation of the throttle control device shown diagrammatically in Figure 6;

Figure 8 is a sectional elevation of a vacuum control valve and its operating solenoids;

Figure 9 is a section on the line 9—9 of Figure 8;

Figures 10, 11 and 12 show a switch arrangement for operating the throttle control device shown in Figure 6, Figure 9 being a side view and Figures 11 and 12 being sections on the lines 11—11 and 12—12 of Figure 10 respectively;

Figure 13 is a view of another switch mechanism for operating the throttle control device shown in Figure 6, looking along the steering column of a vehicle to which the switch mechanism is attached;

Figure 14 is a section on the line 14—14 of Figure 13; and

Figure 15 is a view similar to Figure 7 showing a modification.

Referring to Figures 1 to 5 of the drawings, and more particularly to Figure 1, the throttle control device is shown at 20, and a liquid pressure operated gear-changing mechanism at 21. The mechanism 21 operates a gear-box (not shown) of the well-known synchro-mesh type having four forward gears and reverse, through two links 22 and 23 which effect respectively the selection of the appropriate shift bar of the gear-box and the movement of the selected shift bar to engage the gear. The mechanism 21 comprises a double-acting liquid pressure cylinder 24 in which is operable a piston 25 provided with cams with which co-operate followers mounted on bell-crank levers pivoted to the links 22 and 23. Liquid is supplied to the cylinder 24 from a suitable pressure source through a sliding plunger valve 26 of known type having a follow-

up action the valve being closed when its plunger is in an intermediate position, and being opened by movement of the plunger in either direction, movement in one direction admitting liquid to one end of the cylinder and allowing it to escape from the other end, whilst movement in the opposite direction admits liquid to the said other end of the cylinder, and allows liquid to escape from the said first end.

The valve 26 is operated through a rod 27 and floating lever 28 from a hand lever 29 movable in a quadrant 30, the floating lever 28 being pivoted to a link 31 itself pivoted at one end to a bell-crank lever 32 carrying a cam follower engaging a cam surface on the piston 25, and coupled at its other end to a return spring 33. The hand lever 29 moves towards the left for downward gear changes, and towards the right for upward gear changes, the plunger of the valve 26 moving in the opposite direction in each case, owing to the reversing action of the floating lever 28. The valve plunger extends right through the valve casing and carries an abutment 34 co-operating with the operating plungers of two electric switches 35 and 36 (Figure 2), both of which are open when the valve 26 is in its closed position, the switch 35 being closed by movement of the valve to the left in Figure 1 and the switch 36 by movement of the valve to the right in Figure 1. The follow-up action of the valve 26 is produced by the movement of the bell-crank lever 32 resulting from movement of the piston 25, the arrangement being such that the plunger of the valve 26 returns to its intermediate position when a selected gear has been engaged. Thus the selection of any gear by movement of the lever 29 closes one of the switches 35 or 36, and the engagement of the gear re-opens that switch, the other switch remaining open throughout the gear-changing operation.

The throttle control device 20 is shown in detail in Figures 3, 4 and 5. In those figures, 37 is the main passage in the carburettor body through which the mixture flows to the induction manifold of the engine, and 38 is the throttle valve, which is mounted on a spindle 39 projecting outwardly at one end, the projecting end passing through a sleeve 40 screwed into the carburettor body and itself projecting to form a bearing for a boss carrying an arm 41 connected by a cable 42 to a normal throttle control pedal, and connected also to a return spring 43 anchored at a suitable point on the engine. Secured to the projecting end of the spindle 39 is another arm 44, and a tension spring 45 is connected between pins 46 and 47 on the arms 41 and 44, the spring 45 tending to urge the two arms to relative positions in which the line of action of the said spring is radial to the spindle 39, as shown in Figure 3. The arm 44 carries a pin 48, offset with respect to the axis of the spindle 39, so that it moves through an arcuate path as the throttle valve 38 opens or closes.

A bracket 49 suitably secured to the carburettor body supports two co-axial solenoids 50 and 51, the armatures 52 and 53 of which carry slotted heads 54 and 55 into the slots of which the pin 48 projects. When the solenoids are de-energised, the heads 54 and 55 occupy the positions shown in Figure 3, in which their slots coincide, and the pin 48 is free to move through an angle sufficient to allow the full normal range of movement of the throttle valve. The switches 35 and 36 respectively act to close electric circuits including the solenoids 50 and 51, so that

the solenoid 50 is energised when an upward gear change is effected, and the solenoid 51 is energised when a downward gear change is effected. A switch 56 (Figure 1), controlled by the engagement of its operating plunger with the rod 27, is held in the closed position when the hand lever 29 is in a position for selecting any of the forward gears, but is opened when the hand lever 29 is moved to the neutral or reverse positions, by the operating plunger riding on to a reduced portion 57 of the rod, the switch 56 being in series with both the switches 35 and 36, so that, when it is open, the closing of these switches does not energise the solenoids.

When the solenoid 50 is energised, the armature 52 thereof is drawn into the coil, thus moving the head 54 to the right, so that the left-hand end of the slot therein acts as a stop to limit the movement of the pin 48 to the left, and so to limit the opening of the throttle valve, for example to one eighth of its full opening movement. If the throttle valve is more than one eighth open, the arm 44 is turned as the head 54 moves to reduce the throttle opening, the arm 44 being turned relative to the arm 41 and tensioning the spring 45, so that the position of the normal throttle control is unaffected.

When the solenoid 51 is energised, the armature 53 is drawn into the coil of that solenoid, thus moving the head 55 to the left so that the right hand end of the slot therein acts as a stop to limit the movement of the pin 48 to the right, and so limits the closing of the throttle, for example to a position in which it is three-eighths open. The throttle valve is moved towards the open position if necessary, with relative movement of the arms 41 and 44.

Thus each time the hand lever 29 is moved to the right to make an upward gear change, the switch 35 is closed, energising the solenoid 50. The throttle valve 38 is therefore set to a position in which it is not more than one eighth open, regardless of the position of the throttle pedal, and remains in that position until the higher gear is engaged and the solenoid 50 de-energised, when, if the throttle pedal has been kept in a depressed position, the throttle valve re-opens to a position corresponding to the pedal position.

When the hand lever 29 is moved to the left to make a downward gear change, the switch 36 is closed to energise the solenoid 51, and the throttle valve 38, if it is less than three-eighths open, is moved with the head 55, so that it is at least three-eighths open, regardless of the position of the throttle pedal. The head 55 remains in its operative position until the lower gear is engaged and the solenoid 51 de-energised, allowing the throttle valve to close if the throttle pedal has been released.

Figure 6 shows a form of throttle control device in which the throttle stops are actuated by suction derived from the suction manifold of the engine, the application of the suction being controlled electrically, the throttle control being associated with gear change mechanism of the synchro-mesh type in which the gear changes are effected mechanically by movement of a lever mounted on a rod extending parallel to the steering column, the rod being moved axially to select the appropriate shift bar of the gear-box, and angularly to engage the gears. The throttle control unit is shown at 60, the electrically operated vacuum control valve at 61, and the con-

trol switch at 62. A vacuum reservoir is shown at 63.

The throttle control unit 60 is shown in detail in Figure 7, the spindle of the throttle valve being shown at 64. The carburettor and throttle valve are not shown in the drawings. A sector-shaped plate 65 is fixedly mounted on the throttle valve spindle 64, and a pin 66 projects from one side of the plate 65, at a point off-set from the axis of the spindle 64, to co-operate with two movable stops 67 and 68. Pivotally attached to the other side of the plate 65 is one end of a resilient link 69, the other end of which is pivoted to a lever 70 connected by a cable 71 to the normal throttle control. A return spring 72 for urging the throttle valve to the closed position is also connected to the lever 70. The resilient link 69 comprises inner and outer telescoping members 73 and 74, the inner member 73 having a pair of opposed external shoulders 75 and 76, and the outer member having a pair of opposed internal shoulders 77 and 78, the two pair of shoulders being equally spaced. A pair of sleeves 79, urged apart by springs 80 between which is interposed a washer 81, co-operate with the shoulders to urge the members 73 and 74 to a position in which the shoulders 75 and 77 are in a common plane and the shoulders 76 and 78 are in another common plane, extension or compression of the link causing compression of the springs.

The stops 67 and 68 are associated respectively with bellows 82 and 83. The bellows 82 has an inner end plate 84 fixed to a bracket 85, the stop 67 being carried by a rod 86 passing through the inner end plate 84 and secured to the outer end plate 87 of the bellows, and a spring 88 being incorporated in the bellows to extend it. The bellows 83 has inner and outer end plates 89 and 90 both fixed to a bracket 91, and a movable intermediate plate 92 carrying a rod 93 slidable in the inner end plate 89, the rod 93 carrying the stop 68. The bellows 82, and the chamber 94 of the bellows 83 between the outer end plate 89 and the intermediate plate 92 have a common connection to the vacuum control valve 61, and the other chamber 95 of the bellows 83 has a separate connection to the vacuum control valve 61. A spring 96 in the chamber 95 urges the intermediate plate 92 outwardly.

The vacuum control valve, which is shown in detail in Figures 8 and 9, comprises a body 97 having an axial bore 98 which is counterbored at both ends to provide recesses 99 and 100, the recesses being closed by end caps 101, 102 formed with central openings 103 and 104 respectively leading into chambers 105 and 106 in the end caps. A pipe 107, connected to the inlet manifold of the engine, leads into the bore 98, a non-return valve 108 being provided to prevent flow of air into the bore 98 from the inlet manifold. Another pipe 109 connects the bore 98 to the vacuum reservoir 63. A pipe 110 leads from the recess 99 to the chamber 95 in the bellows 83, and a pipe 111 leads from the recess 100 to the chamber 94 in the bellows 83, and to the bellows 82. Another pipe 112 leads from the recess 99 to a vacuum cylinder (not shown) for disengaging the clutch of the vehicle. The recess 100 and the chamber 105 are connected together by passages 113 (Figure 9). Solenoids 114 and 115 are mounted respectively on the end caps 101 and 102, the armatures of the solenoids carrying respectively valve heads 116 and 117 located in the recesses 99 and 100. The armatures are urged

inwardly by springs 118 and 119 respectively to seat the valve heads on the shoulders at the inner ends of the recesses so as to close the ends of the bore 98, energisation of the respective solenoids drawing the valve heads outwardly so that they close respectively the openings 103 and 104 in the end caps 101 and 102. Air inlet ports 120 are provided in the end cap 102.

When both solenoids are de-energised, both 10 valve heads are in their inner positions, and the three pipes 110, 111 and 112 are connected to the atmosphere through the ports 120, so that both stops 67 and 68 are withdrawn from their operative positions. When the solenoid 115 is energised, the recesses 99 and 100 are cut off from the ports 120, and suction is applied to all three pipes 110, 111 and 112. As the suction acts on both sides of the intermediate plate 92 in the bellows 83, the stop 68 is not affected, but the suction acting in the bellows 82 draws the end plate 87 towards the end plate 84, thus moving the stop 67 inwardly to reduce the throttle opening to a small value, if it is wide open, or to limit its opening. Suction is also applied to the clutch 20 vacuum cylinder to disengage the clutch. When the solenoid 114 is energised, the pipes 110 and 112 only are connected to suction, so that the intermediate plate 92 of the bellows 83 is displaced inwardly to open the throttle valve or 25 prevent it from closing, and suction is applied to the clutch vacuum cylinder to hold the clutch disengaged, the bellows 82, and the chamber 95 in the bellows 83, remaining connected to the atmosphere.

30 The bellows 82 and 83 may be replaced by cylinders, the stops 67 and 68 being secured to pistons slidable in the said cylinders.

Figures 10, 11 and 12 show the operating mechanism for the switch 62, the switch itself, which 40 is of the double pole type, being mounted on the steering column 121 of the vehicle. The operating plunger 122 of the switch is operated by cam strips 123 secured to the gear-change rod 124, the cam strips being so positioned on the rod 124 45 that the plunger is depressed only when a gear is fully engaged. The switch 62 is mounted on a pipe clip 125 which is clamped onto the steering column 121, the pipe clip having secured to it two diametrically opposed ears 126, 128. A bracket 127 clamped to the gear-change rod 124 carries a rocking arm 128, and two tension springs 129, 130 extend between the ears 126 and the arm 128, the springs tending to urge the rod in either direction from a dead-centre position 50 to hold it in a position corresponding to full engagement of any gear.

The contacts of the switch 62 which are closed 55 when the operating plunger 122 is depressed, are in the circuit of the solenoid 114, which circuit 60 also includes contacts closed only when the clutch of the vehicle is disengaged and its driving member is revolving at a lower speed than its driven member. The other contacts of the switch 62, which are closed when the operating 65 plunger 122 is free, are in the circuit of the solenoid 115. Therefore, when any gear is engaged and the clutch also is engaged, both circuits are open. The sequence of operations during gear changing is as follows. When the gear lever is moved to disengage a gear, the operating plunger 122 is released, and the circuit of the solenoid 115 is closed, causing the throttle stop 67 to be moved inwardly, thus nearly closing the throttle 70 if it is not already closed, and disengaging the clutch. The continued movement of the gear

lever engages the fresh gear, opening the previously closed contacts of the switch 62, and closing the contacts thereof in the circuit of the solenoid 114. If the driving member of the clutch is revolving at a lower speed than the driven member, the circuit of the solenoid 114 is closed, and the throttle stop 63 is moved inwardly to speed up the engine until the driving member slightly overruns the driven member, the clutch being meanwhile held disengaged. When the driving member begins to overrun, the clutch-controlled switch is opened, and the solenoid 114 is de-energised, thus allowing the clutch to engage, and the stop 63 to be withdrawn.

Figures 13 and 14 show a modified arrangement of the mechanism for operating the switch 62. The switch is secured to the steering column 121 by a two-piece clamp 136, and its operating plunger 122 is actuated by a lever 131 pivoted at 132 on the clamp. The lever 131 carries a roller 133 acting as a cam follower, and the gear change rod 124 carries five cams 134, 135, 136, 137 and 138 so placed that the cams 134 and 135 are engaged with the roller when the gear lever is engaged with the third and fourth gear shift bar, the cams 136 and 137 are engaged with the roller when the gear lever is engaged with the first and second gear shift bar, and the cam 138 is engaged with the roller when the gear lever is engaged with the reverse gear shift bar. Each cam has a notch such as those shown at 139 in Figure 13 to receive the roller when the corresponding gear is engaged, and the cams are individually adjustable on the rod 124.

Figure 15 shows a modified arrangement for connecting the normal throttle control cable 71 to the throttle valve. The valve spindle 64 carries an arm 140 fixed thereto and supporting the pin 66 which co-operates with the throttle stops 67 and 68, these stops being operated by the bellows 82 and 83 as described with reference to Figure 7. The cable 71 is attached to another arm 141 which is free to turn on the spindle 64, and is engaged between the two arms of a somewhat U-shaped leaf spring 142 fixed to the arm 140. Thus the cable 71 is normally able to operate the throttle valve through the leaf spring 142, but, if either stop 67 or 68 is moved to limit the throttle valve movement, and the normal throttle control is held in a position to set the throttle to a position outside the limited range, the spring 142 can yield.

Only one stop may be provided, which is rendered operative to set the throttle valve within a predetermined range for all gear changes, or for changes in one direction only.

I claim:

1. In a motor vehicle including an engine, throttle valve means for controlling the speed of the engine, a change-speed gearbox through which wheels of the vehicle are driven by the engine, means for engaging and disengaging the various gear ratios of the gearbox, and a friction clutch including driving and driven members between the engine and the gearbox, throttle control means including a driver operated throttle control member, means connecting said driver operated throttle control member to the throttle valve, a resilient connection in said connecting means enabling the throttle valve to move independently of the driver-operated throttle control member, a stop contacting member moving with the throttle valve, two movable stops co-operating with said stop-contacting member, one of said stops having an operative position in

which it limits the opening of the throttle valve and the other of said stops having an operative position in which it limits the closing of said throttle valve, stop actuating means for moving the first-mentioned stop to its operative position, separate stop actuating means for moving the second-mentioned stop to its operative position, said first stop actuating means being actuated by the gear engaging and disengaging means to disengage any gear ratio, said second stop actuating means being actuated by movement of the gear engaging and disengaging means to engage a gear ratio, and being subsequently returned from its operative position upon the attainment of synchronism between the driving and driven members of the friction clutch.

2. In a motor vehicle including an engine, throttle valve means for controlling the speed of the engine, a change speed gear box through which wheels of the vehicle are driven by the engine, and means for engaging and disengaging the various gear ratios of the gearbox, throttle control means including a driver-operated throttle control member, means connecting said driver-operated throttle control member to the throttle valve, a resilient connection in said connecting means enabling the throttle valve to move independently of the driver-operated throttle control member, a stop-contacting member moving with the throttle valve, a movable stop co-operating with said stop-contacting member, a solenoid, an armature in said solenoid carrying said stop, a source of electric current, switch means for controlling the connection of said solenoid to said electric current source, said solenoid, when energized, moving the stop from a position in which it allows the throttle valve to move through its full range to a position in which it restricts the throttle valve movement to a limited range, and switch operating means actuated by the gear engaging and disengaging means to close the switch when the said means is operated to disengage any gear ratio.

3. In a motor vehicle including an engine, throttle valve means for controlling the speed of the engine, a change-speed gearbox through which wheels of the vehicle are driven by the engine, and means for engaging and disengaging the various gear ratios of the gearbox, throttle control means including a driver-operated throttle control member, means connecting said driver-operated throttle control member to the throttle valve, a resilient connection in said connecting means enabling the throttle valve to move independently of the driver-operated throttle control member, a stop-contacting member moving with the throttle valve, first and second movable stops co-operating with said stop-contacting member, said first stop having an operative position in which it limits the opening of the throttle valve and said second stop having an operative position in which it limits the closing of the throttle valve, a first solenoid operatively connected to said first stop, a second solenoid operatively connected to said second stop, a source of electric current, first switch means controlling the connection of said first solenoid to the current source, second switch means controlling the connection of said second solenoid to the current source, and means operated by the gear engaging and disengaging means for selectively operating said first and second switch means respectively when said gear engaging and disengaging means is moved to effect a change to a higher and a lower gear ratio.

4. In a motor vehicle including an engine, throttle valve means for controlling the speed of the engine, a change-speed gear box through which wheels of the vehicle are driven by the engine, means for engaging and disengaging the various gear ratios of the gearbox, and a friction clutch including driving and driven members interposed between the engine and the gearbox, throttle control means including a driver-operated throttle control member, means connecting said driver-operated throttle control member to the throttle valve, a resilient connection in said connecting means enabling the throttle valve to move independently of the driver-operated throttle control member, a stop-contacting member moving with the throttle valve, first and second movable stops co-operating with said stop-contacting member, said first stop having an operative position in which it limits the opening of the throttle valve and said second stop having an operative position in which it limits the closing of the throttle valve, a first fluid actuator operatively connected to said first stop to move it to its operative position, a second fluid actuator operatively connected to said second stop to move it to its operative position, a source of working fluid, valve means controlling the supply of working fluid from said source to said first and second fluid actuators and valve control means responsive to movement of said gear engaging and disengaging means and to synchronism between said driving and driven clutch members, said valve control means controlling the valve means to effect operation of the first fluid actuator when the gear engaging and disengaging means is moved to the neutral position, to effect operation of the second fluid actuator when the gear engaging and disengaging means is moved to engage a gear ratio, and to return said second actuator to its inoperative position when the driving and driven members of the friction clutch are synchronized.

5. In a motor vehicle including an engine, throttle valve means for controlling the speed of the engine, a change-speed gear box through which wheels of the vehicle are driven by the engine, means for engaging and disengaging the various gear ratios of the gearbox, and a friction clutch including driving and driven members interposed between the engine and the gearbox, throttle control means including a driver-operated throttle control member, means connecting said driver-operated throttle control member to the throttle valve, a resilient connection in said connecting means enabling the throttle valve to move independently of the driver-operated throttle control member, a stop-contacting member moving with the throttle valve, first and second movable stops co-operating with said stop-contacting member, said first stop having an operative position in which it limits the opening of the throttle valve and said second stop having an operative position in which it limits the closing of the throttle valve, a first fluid actuator operatively connected to said first stop to move it to its operative position, a second fluid actuator operatively connected to said second stop to move it to its operative position, a source of working fluid, valve means controlling the supply of working fluid from said source to said first and second fluid actuators, solenoid means operating said valve means, a source of electric current, switch means operated by the gear engaging and disengaging means, and

switch means operated by the clutch, the switch means operated by the gear engaging and disengaging means operating the valve means to effect operation of the first fluid actuator when the gear selecting means is moved to the neutral position and to effect operation of the second fluid actuator when the gear engaging and disengaging means is moved to engage a gear ratio, and the switch means operated by the clutch operating the valve means to return the second actuator to its inoperative position when the driving and driven members of the clutch are synchronized.

6. In a motor vehicle including an engine, throttle valve means for controlling the speed of the engine, a change speed gearbox through which wheels of the vehicle are driven by the engine, manually operated means for engaging and disengaging the various gear ratios of the gearbox, and a friction clutch including driving and driven members interposed between the engine and the gearbox, throttle control means including a driver operated throttle control member, means connecting said driver operated throttle control member to the throttle valve, a resilient connection in said connecting means enabling the throttle valve to move independently of the driver-operated throttle control member, a stop-contacting member moving with the throttle valve, first and second stops co-operating with said stop-contacting member, first and second fluid actuators, means connecting said first and second fluid actuators respectively to said first and second stops, a source of working fluid, valve means controlling the supply of working fluid from said source to said fluid actuators, solenoid means operating said valve means, a source of electric current, switch means operated by the manually operated gear engaging and disengaging means, and switch means operated by the clutch, the switch means operated by the manually operated gear engaging and disengaging means operating the valve means, when the said gear engaging and disengaging means is moved to the neutral position, to effect operation of the first fluid actuator and thereby position the first stop to limit the opening of the throttle valve, and operating the said valve means when the said gear engaging and disengaging means is moved to engage a gear ratio, to effect operation of the second fluid actuator and thereby position the second stop to limit closing of the throttle valve, and the switch means operated by the clutch operating the valve means when the speeds of the driving and driven clutch members are synchronized, to return the second actuator to its inoperative position.

SYDNEY MACDONALD PARKER.
